C. W. C. COOPER

HEADLIGHT DIMMER

Filed Feb. 12, 1924

UNITED STATES PATENT OFFICE.

CARL W. C. COOPER, OF HUNTINGTON, INDIANA.

HEADLIGHT DIMMER.

Application filed February 12, 1924. Serial No. 692,448.

To all whom it may concern:

Be it known that CARL W. C. COOPER, citizen of the United States, residing at Huntington, in the county of Huntington and State of Indiana, has invented certain new and useful Improvements in Headlight Dimmers, of which the following is a specification.

My invention relates to improvements in headlights and more particularly to an attachment for dimming the headlights of vehicles.

The primary object of the invention is to provide an electrically operated curtain movable to cover the lower portion of the lens of the headlight to obstruct the ray of light projected from the lower half of the reflector.

A further object of the invention is to provide a curtain wholly mounted within the casing of the headlight to protect it from the weather.

Another object is to provide a device of the above-mentioned character which is simple and durable in construction, reliable in operation, and inexpensive to manufacture.

Other objects and advantages of the invention will be apparent during the course of the following description.

30 In the accompanying drawing forming a part of this specification and in which like numerals are employed to designate like parts throughout the same,

Figure 1, is a perspective view of a headlight constructed in accordance with my invention, and,

Figure 2, is a fragmentary vertical sectional view of the same.

In the drawing, wherein for the purpose 40 of illustration I have shown a preferred embodiment of my invention, the numeral 5 designates a casing rounded at the top and square at the bottom, housing the bulb 5' and reflector 9. The front of the casing is 45 equipped with a removable cover 6 held in position by the pintle pins 7 at each side. The cover is provided with a circular opening covered by the usual lens 8 to permit the emission of light rays cast outwardly, from 50 within the casing, by the reflector 9.

A spring roller 10 is mounted in brackets 11 secured to opposite sides of the casing adjacent the bottom thereof, and below the periphery of the lens. A curtain 12 constructed of any non-translucent material is wound

on the roller 10 having one end permanently attached thereto. A stiffening rod 13 extends across the free end of the curtain, its ends being slidably mounted in the vertical guides 14 at each side of the casing. A metal lug 15 is attached to each end of the rod 13 being positioned to the rear thereof. Mounted above the lugs 15 and in vertical alignment therewith are a pair of electromagnets 16 arranged on a horizontal plane 65 with the center of the lens. Wires 17 lead from the magnets to a battery and switch (not shown), through the medium of which the magnets are energized attracting the lugs 15 which raise the curtain covering the 70 lower half of the lens. To provide for the passage of the curtain an opening 18 is cut through the reflector. When the magnets are de-energized the spring roller will 75 rewind the curtain.

Thus, it is seen when operating the vehicle at night the headlights may be rendered glareless by raising the curtain to cover the lower half of the lens, when approaching 80 pedestrians and vehicles moving in the opposite direction.

It is to be understood that the form of my invention herewith shown and described is to be taken as a preferred example of the same, and that certain changes in the shape, 85 size, and arrangement of parts may be resorted to without departing from the spirit of the invention or the scope of the subjoined claims.

Having thus fully described my invention, I claim:

1. In combination with a headlight, a roller mounted within said casing, a curtain wound on said roller, lugs carried by said curtain and magnetic means for attracting said lugs to unwind said curtain.

2. In combination with a headlight, a spring roller mounted in the bottom thereof, a curtain wound on said roller, lugs attached to the free corners of the curtain, and a pair 100 of electromagnets positioned above said lugs, adapted to raise said curtain when energized.

3. In combination with a headlight, a spring roller mounted within said casing 105 below the lens thereof, a curtain wound on said roller, guides at the side of said casing, a rod secured to the free end of said curtain having its ends slidably mounted in said guides, lugs projected at right angles from 110

said rod, and a pair of electromagnets positioned above said lugs, adapted to attract the same when energized.

4. In combination with a headlight, a spring roller mounted within said casing, a curtain wound on said roller, lugs carried by said curtain and magnetic means for attracting said lugs to unwind said curtain against the tension of said roller.

10 5. In combination with a headlight, a spring roller mounted within said casing, a curtain wound on said roller, means for guiding said curtain, a rod secured to the free end of said curtain, lugs carried by said rod adjacent the ends thereof, and magnets positioned on opposite sides of the casing on a horizontal plane with the center of the lens, adapted to attract said lugs when energized.

20 6. In combination with a headlight, a spring roller mounted within said headlight, a curtain wound on said roller, guides at the side of said headlight, a rod extending across the end of said curtain movable in said guides, and electromagnets positioned above said rod, adapted to raise said curtain when energized.

7. In a device of the character described,

the combination with a headlight having reflector, of a spring roller mounted beneath said reflector, a curtain wound on said roller, lugs secured to the corners of said curtain, said reflector having a slot for the passage of said curtain therethrough, and electromagnets for attracting said lugs when energized.

8. In combination with a headlight, a roller mounted within said headlight, a curtain wound on said roller, lugs carried by said curtain, electromagnets for attracting said lugs to unwind said curtain, and means for rewinding said curtain when released by said electromagnets.

9. In combination with a headlight, a roller mounted within said headlight, a curtain wound on said roller, guides at the side of said headlight, a rod secured to the end of said curtain movable in said guides, lugs secured to said rod, electromagnets adapted to attract said lugs and unwind said curtain when energized, and spring means for re-winding said curtain when said magnets are de-energized.

In testimony whereof I affix my signature.

CARL W. C. COOPER
